EDGER-TRIMMER

Melvin H. Boldt, Glenview, Ill., assignor to G. W.
Murphy Industries, Inc., Houston, Tex.

Filed Nov. 16, 1970, Ser. No. 25,992

Term of patent 14 years

Int. Cl. D8—03, 05

U.S. Cl. D8—8

Fig.-1

Fig.-2

Fig.-3

Fig - 4

Fig - 5

FIG. 6

FIG. 7

FIG. 1 is a perspective view of an edger-trimmer, showing my new design;

FIG. 2 is a rear elevational view of the edger-trimmer illustrated in FIG. 1;

FIG. 3 is a front elevational view of the edger-trimmer illustrated in FIG. 1;

FIG. 4 is a right side elevational view of the edger-trimmer illustrated in FIG. 1;

FIG. 5 is a bottom plan view of the edger-trimmer illustrated in FIG. 1;

FIG. 6 is a top plan view of the edger-trimmer illustrated in FIG. 1; and

FIG. 7 is a left side elevational view of the edger-trimmer illustrated in FIG. 1.

The broken line showings of a blade and handle are for illustrative purposes only.

I claim:

The ornamental design for an edger-trimmer, as shown and described.
